(57) **CLAIM**

The ornamental design for a patient interface cushion module, as shown and described.

DESCRIPTION

FIG. 1 is a front perspective view of a patient interface cushion module showing a first embodiment of our new design;

FIG. 2 is another perspective and with the cushion module shown in isolation;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a reverse perspective view thereof;

FIG. 10 is a front perspective view of a patient interface cushion module showing a second embodiment of our new design;

FIG. 11 is another perspective and with the cushion module shown in isolation;

FIG. 12 is a front view thereof;

FIG. 13 is a rear view thereof;

FIG. 14 is a top view thereof;

FIG. 15 is a bottom view thereof;

FIG. 16 is a right side view thereof;

FIG. 17 is a left side view thereof; and,

FIG. 18 is a reverse perspective view thereof.

The broken lines represent portions of the patient interface cushion module and do not form a part of the claimed design.

(Continued)

In FIGS. 1-9, the combination of line shading and stippling is to convey a contrast in appearance.
